CANE-DOLL

Fern Carver, Chicago, Ill.

Application February 9, 1953, Serial No. 23,489

Term of patent 3½ years

(Cl. D34—4)

To all whom it may concern:

Be it known that I, Fern Carver, a citizen of the United States of America, residing at Chicago, in the county of Cook and State of Illinois, have invented a new, original, and ornamental Design for Cane-Doll, of which the following is a specification, reference being had to the accompanying drawing, forming part thereof.

Figs. 2, 3, 4 and 5 are rear, side, top and bottom views, respectively, of the device of Fig. 1.

I claim:

The ornamental design for a cane-doll, as shown.

FERN CARVER.
